CLAIM

The ornamental design for a helical fluted forward and reverse rotation cutting tool, as shown and described.

DESCRIPTION

FIG. 1 is a front end perspective view of the helical fluted forward and reverse rotation cutting tool of the present invention;

FIG. 2 is a left side view thereof;

FIG. 3 is a right side view thereof;

FIG. 4 is a rear view thereof;

FIG. 5 is a front view thereof;

FIG. 6 is an end view thereof; and,

FIG. 7 is a rear end view thereof.

1 Claim, 6 Drawing Sheets
